(57) **CLAIM**

I claim the ornamental design for a handheld electronic device case, as shown and described.

DESCRIPTION

FIG. 1 is a back perspective view of a handheld electronic device case;

FIG. 2 is a front perspective view of the handheld electronic device case;

FIG. 3 is a front elevational view thereof;

FIG. 4 is a back elevational view thereof;

FIG. 5 is a right elevational view thereof;

FIG. 6 is a left elevational view thereof;

FIG. 7 is a top plan view thereof; and,

FIG. 8 is a bottom plan view thereof.

The dashed lines in the drawings represent stitching which forms part of the claimed design.
